UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,339,002.

Specification of Letters Patent.

Patented May 4, 1920.

Application filed September 25, 1919. Serial No. 326,129.

To all whom it may concern:

Be it known that I, ALONZO E. RHOADES, a citizen of the United States, residing at Hopedale, in the county of Worcester and 5 State of Massachusetts, have invented an Improvement in Feeler Mechanism for Looms, of which the following description, in connection with the accompanying drawings, is a specification, like characters on 10 the drawings representing like parts.

This invention relates to feeler mechanisms for looms, and more particularly to that type of feeler mechanisms, wherein the feeler arm or member is moved in a direction longitudinally of the shuttle when the filling becomes substantially exhausted, to thereby set in operation a train of mechanism for replenishing the filling.

In this type of feeler mechanisms, the 20 feeler tip or end of the feeler arm is usually provided with a roughened or toothed surface which, by engagement with the filling, prevents movement of the feeler arm in a direction longitudinally of the shuttle on 25 a detecting beat until the filling becomes substantially exhausted, and then the teeth of the feeler tip no longer being held by the working supply of filling, the feeler arm is given its described movement. The con- 30 stant impact of the feeler tip against the filling which occurs on each detecting beat, sometimes injuriously effects the filling or weft thread, and it has heretofore been suggested to form the contacting end of the 35 feeler tip by some soft substance such as felt which would not injure the filling by contact therewith. Inasmuch, however, as the movement of the feeler arm longitudinally of the shuttle is to be restrained by 40 engagement of the end of the tip with the filling when a working supply is present, the frictional engagement of the filling with the felt on the end of the feeler arm is not sufficiently reliable to effect this purpose, 45 and the feeler arm is liable at times to par- 50 take of its movement longitudinally of the shuttle when a working supply of filling is present, thereby causing waste and im- proper operation of the loom.

An important feature of the present invention, therefore, consists in a feeler arm yieldingly movable toward and from the front of the loom, and having a feeler tip on which is yieldingly mounted a feeler holding point or points which serve to take

the first impact of the filling and enter between the coils thereof and then yield frontwardly under the frontward push of the filling until the end of the feeler tip itself engages the filling and causes the feeler 60 arm to be moved frontwardly thereby. When the filling reaches a condition of substantial exhaustion, the feeler point or points will again take the first impact of the advancing filling carrier and then yield 65 inwardly until the surface or end of the feeler tip engages the filling carrier, whereupon the surface of the feeler tip and feeler holding point or points will move in a direction longitudinally of the shuttle along 70 the surface of the filling carrier.

The present invention may be advantageously employed in connection with any character of feeler arm which is mounted for movement longitudinally of the shuttle 75 when the filling is substantially exhausted, but has special advantages in connection with the character of feeler arm and associated parts shown and described in the patent to Edward S. Stimpson, No. 1,309,226, and 80 consequently, in the following description, the invention will be set forth as applied to or associated with that character of feeler mechanism.

In the drawing:—

Figure 1 is a plan view, substantially similar in all respects to Fig. 1 of the Stimpson patent, but having the present invention applied thereto;

Fig. 2 is an enlarged side elevation showing more particularly the end of the feeler arm, the feeler tip, and the yieldingly mounted feeler holding points carried by the feeler tip;

Fig. 3 is a section on the line 3—3 of Fig. 95 2, showing the operation of the feeler arm and feeler points when a working supply of filling is present in the shuttle on a detecting beat;

Fig. 4 is a view similar to that of Fig. 3, 100 but showing the action of the parts when the filling is substantially exhausted;

Fig. 5 is a sectional view of a feeler tip with a single feeler holding point yieldingly mounted thereon; and

Fig. 6 is an enlarged detail showing more particularly the general construction of the feeler holding point or points.

The loom frame 1 has mounted thereon the transverse or change shaft 2 from which 110

rises the arm 3 to which is pivotally connected the transmitter 4. A latch 5 is pivotally mounted on the transmitter at 6, and its rear end portion is adapted at times to be engaged by an operating member 7, which in the present instance is a part associated with the weft hammer or cam follower.

Underlying the finger 8 connected to the latch 5 is the arm 9 of a lever pivotally mounted at 10 to a supporting arm 11, and to the lever 9 is jointed the connecting rod 12 which has its other end joined to a controller 13 through an enlarged slot in which passes the feeler arm or member 14. The feeler arm 14 is supported in a direction inclined to the longitudinal axis of the shuttle upon a feeler stand 15, and has secured thereto a slide 16 resting upon the support or stand 15. The front end portion of the feeler arm 14 passes through a swivel block or guide 17 mounted upon the feeler stand. The parts so far described are the same as the similar parts shown and described in the Stimpson patent heretofore mentioned, and to which reference may be had for further detailed description thereof.

The lay 18 carries the usual shuttle-box, the front wall of which is provided with a slot 19 adapted to register with a slot 20 formed in the front wall of the shuttle 21 when it is in the detecting box, the construction being such that as the lay moves frontwardly on a detecting beat, the feeler member 14 may enter the shuttle and feel for the condition of the filling.

The feeler arm 14 is provided with a feeler tip 22 which may be connected thereto by a pin 23, and the rear face or surface 24 of the feeler tip which, as will more fully appear, is adapted to engage a surface within the shuttle on each detecting beat, and is formed as a smooth, broad surface best shown in Fig. 2. The broad surface 24 at the end of the feeler tip affords an enlarged bearing against which the filling may contact without injurious effect under the conditions to be presently described.

As indicated in Figs. 3 and 4, the feeler tip 22 is provided with feeler points, two being shown, mounted yieldingly upon the feeler tip and normally extending rearward of the contacting end 24 of the feeler tip. In the present instance, the feeler holding points 25 are mounted in guideways 26 formed in the feeler tip, and extend frontwardly into an enlarged recessed portion 27 formed in the feeler tip. Each of the feeler holding points 25 is provided with a collar 28 between which and a fixed bushing 29 at the front end portion of the feeler tip is interposed a spring 30 normally tending to project the associated feeler point to extend its end portion beyond the broad end portion 24 of the feeler tip.

65 The feeler holding points 25 are similarly

formed, and one of them is indicated in Fig. 6, wherein it will be noted that the extreme end portion 31 is rounded over, the effect being that when the filling engages the end of the feeler holding point, the latter will enter between the coils of the filling or weft without injuriously effecting or cutting it.

Instead of mounting two feeler holding points on the feeler tip, one may sometimes be sufficient, as indicated in Fig. 5, wherein the feeler tip is formed integral with the feeler arm, but as in the construction heretofore described, the feeler tip has the broad flattened engaging surface similar to the surface 24 already described. In the constriction indicated in Fig. 5 wherein a single feeler point is associated with the feeler tip, the feeler tip may be bored longitudinally as indicated at 32 to form the recess 33 in which the spring 34 may be seated, one end thereof bearing upon the end wall 35 of the recess, and the other end against the collar 28. The end portion of the bored feeler tip may be closed by a plug 36 against which the collar 28 bears under the impulse of the spring 34.

As more fully described in the patent to Stimpson hereinbefore mentioned, the feeler arm 14 is surrounded by a spring 37 (Fig. 1) which normally holds the feeler arm in its rearward position.

When a working supply of filling is present in the shuttle on a detecting beat, the feeler point or points will first engage the filling or weft, and owing to the less strength of the spring 30 than the spring 37, the feeler points will be moved inwardly while held sufficiently firm to cause their rounded end portion 31 to enter between the coils of the filling. After the ends have thus entered between the coils of the filling as indicated in Fig. 3, the feeler points will be moved frontwardly until the broad surface 24 of the feeler tip has engaged the filling mass, and thereupon, the feeler arm will be moved frontwardly by the push upon the broad face 24 of the feeler tip. Owing to the fact that the feeler holding points penetrate between the coils of the filling, the feeler arm will be held from movement longitudinally of the shuttle as it is moved frontwardly. When, however, the filling has become substantially exhausted as indicated in Fig. 4, the feeler holding points will be pushed frontwardly in the feeler tip until the broad surface of the tip itself meets the filling carrier or the few coils of filling still remaining thereon, whereupon the smooth, broadened surface of the feeler tip, and the rounded end portions of the feeler holding points will move longitudinally along the surface of the filling carrier, and effect replenishment of filling. It will be apparent, therefore, that the first impact of the surface in the shuttle on a detecting beat will be against 130

the ends of the feeler holding points, whereupon such points will yield relative to the feeler tip and permit a subsequent engagement of the broad or flattened end portion 5 of the feeler tip with the surface within the shuttle, which thereupon effects frontward movement of the feeler arm.

In the illustrated embodiment of the present invention, where the feeler points are 10 associated with a feeler arm supported in a direction inclined to the longitudinal axis of the shuttle, the feeler holding points are especially advantageous when also inclined relative to the longitudinal axis of the shuttle, because under such conditions, the ends 15 of the feeler points act with positiveness between the coils of the filling to prevent longitudinal movement of the feeler member or arm when a working supply of filling 20 is present, but offer no obstruction to the longitudinal movement of the feeler tip along the feeler carrier when the filling is substantially exhausted. In this latter respect the rounded end portions 31 of the 25 inclined feeler points move along the surface of the filling carrier without injurious effect thereto.

What is claimed is:—

1. In a feeler mechanism for looms, a 30 feeler arm that is mounted for movement longitudinally of the shuttle when the filling is substantially exhausted and is provided with a feeler tip having a smooth end which engages a surface within the shuttle on each 35 detecting beat, a feeler point that has a rounded end adapted to enter between coils of the filling without cutting effect and that is yieldingly mounted upon the feeler tip to extend beyond the smooth end thereof, said 40 feeler point being inclined in the general direction of longitudinal movement of the feeler arm which takes place when the filling is substantially exhausted, and by engagement with a surface in the shuttle prevents 45 movement of the feeler arm longitudinally of the shuttle until the filling is substantially exhausted.

2. In a feeler mechanism for looms, a feeler arm that is mounted for movement 50 longitudinally of the shuttle when the filling or weft is substantially exhausted, and is provided with a feeler tip which contacts with a surface within the shuttle on each detecting beat and is moved frontwardly 55 thereby, and a feeler holding point that is yieldingly mounted upon the feeler tip to extend beyond the end thereof and is inclined in the direction of the longitudinal movement of the feeler arm which takes 60 place when the filling or weft is substantially exhausted on a detecting beat.

3. In a feeler mechanism for looms, a feeler arm that is mounted for movement 65 longitudinally of the shuttle and is provided with a feeler tip which engages a surface

within the shuttle on each detecting beat, and a feeler holding point that is yieldingly mounted on the feeler tip to extend beyond the end of the tip in a direction inclined to the longitudinal axis of the weft carrier in 70 the shuttle, and by engagement with the weft on the carrier prevents movement of the feeler arm longitudinally of the shuttle until substantial exhaustion of filling and thereupon slides along the surface of the 75 weft carrier.

4. In a feeler mechanism for looms, a feeler arm that is mounted for movement longitudinally of the shuttle and is provided with a feeler tip that engages a surface 80 within the shuttle on each detecting beat, and a feeler holding point that is yieldingly mounted on the feeler tip to receive the first impact of the surface within the shuttle, and by engagement therewith to prevent 85 movement of the feeler arm longitudinally of the shuttle on a detecting beat until the filling is substantially exhausted and then 90 movable with the feeler tip longitudinally along the surface of the filling carrier.

5. In a feeler mechanism for looms, the combination of a feeler arm that is mounted for movement longitudinally along the filling carrier in the shuttle when filling is substantially exhausted on a detecting beat, a 95 feeler tip mounted on the feeler arm to engage a surface within the shuttle on a detecting beat, and a feeler holding point yieldingly mounted on the feeler tip to normally extend in an inclined direction beyond the 100 end thereof and receive the first impact of a surface within the shuttle on a detecting beat, and by engagement therewith prevent movement of the feeler arm longitudinally of the shuttle until substantial exhaustion of 105 filling.

6. In a feeler mechanism for looms, the combination of a feeler arm supported for movement toward and from the front of the loom in a path inclined to the longitudinal 110 axis of the shuttle and having a tip, the rear surface of which is adapted to be engaged by a surface within the shuttle on each detecting beat, a feeler holding point yieldingly mounted on the feeler end and 115 supported to normally project beyond the rear engaging surface of the feeler tip and in an inclined position relative to the surface within the shuttle engaged by it.

7. In a feeler mechanism for looms, the combination of a feeler arm having a feeler tip adapted to slide longitudinally along the filling carrier when the filling is substantially exhausted, means for effecting replenishment of filling, and feeler holding points 120 yieldingly supported by the feeler tip to extend beyond the end thereof and receive the first impact on the beat up and then yield to permit the feeler tip to engage the surface, said points acting positively by en- 125

gagement with the filling to prevent movement of the feeler tip longitudinally of the filling carrier until substantial exhaustion of filling.

5. 8. In a feeler mechanism for looms, the combination of a feeler arm, a feeler tip mounted on the feeler arm and having a substantially smooth rear surface which is adapted to engage the filling carrier and slide longitudinally along and in contact with the filling carrier when the filling is substantially exhausted on a detecting beat, and a feeler point that is normally supported on the feeler tip to extend rearwardly 10 of the smooth rear surface of the feeler tip and yield inwardly of the feeler tip by contact with the filling carrier when filling is substantially exhausted on a detecting beat and permit engagement of the smooth rear 15 surface of the tip with the filling carrier.
20. 9. In a feeler mechanism for looms, the combination of a feeler arm, a feeler tip mounted on the feeler arm and having a substantially smooth rear surface which is adapted to engage the filling carrier and slide longitudinally along and in contact with the filling carrier when the filling is substantially exhausted on a detecting beat, 25 and a rounded feeler point that is normally

supported on the feeler tip to extend rearwardly of the smooth rear surface of the feeler tip and yield inwardly of the feeler tip by contact with the filling carrier when filling is substantially exhausted on a detecting beat and permit engagement of the 30 smooth rear surface of the tip with the filling carrier.

10. In a feeler mechanism for looms, the combination of a feeler arm, a feeler tip mounted on the feeler arm and having a 40 substantially smooth rear surface which is adapted to engage the filling carrier and slide longitudinally along and in contact with the filling carrier when the filling is substantially exhausted on a detecting beat, a feeler point supported on the feeler tip, a spring between the feeler tip and feeler point normally forcing the feeler point rearwardly beyond the smooth rear surface of the feeler tip and yieldable under the front- 45 ward pressure on a detecting beat to permit engagement of the smooth rear surface of the feeler tip with a surface within the shuttle.

In testimony whereof, I have signed my 50 name to this specification.

ALONZO E. RHOADES.
